[57] CLAIM

The ornamental design for a fish lure, substantially as shown.

DESCRIPTION

FIG. 1 is a perspective view showing our new design for a fish lure in an articulated position;

FIG. 2 is a front elevational view of the fish lure of FIG. 1;

FIG. 3 is a rear elevational view of the lure;

FIG. 4 is a side elevational view of the lure of FIG. 1;

FIG. 5 is a top view of said lure; and

FIG. 6 is a bottom view of said lure.

FIG. 1

FIG. 2

FIG. 3

FIG. 4

FIG. 5
